COMBINED WHEEL AND JACK ASSEMBLY FOR A HAND-OPERATED PALLET TRUCK

Hans Gustav Ingvar Larsson and Sven Gunnar Harald
Stjarnqvist, Angelholm, Sweden, assignors to Marco
Materialhantering AB

Filed Dec. 27, 1974, Ser. No. 536,806

Claims priority, application Sweden July 1, 1974

Term of patent 14 years

Int. Cl. D12—05

U.S. Cl. D12—60

FIG. 1

FIG. 2

FIG. 3

FIG. 4

FIG. 1 is a perspective view of a combined wheel and jack assembly for a hand-operated pallet truck, embodying our new design.

FIG. 2 is a side elevational view thereof.

FIG. 3 is a back elevational view thereof.

FIG. 4 is a front elevational view thereof.

We claim:

The ornamental design for a combined wheel and jack assembly for a hand-operated pallet truck, as shown.
